CHUCK FOR ROCK DRILLS

Filed May 3, 1928 2 Sheets-Sheet 2

UNITED STATES PATENT OFFICE

AUGUST H. KATTERJOHN, OF DENVER, COLORADO, ASSIGNOR TO GARDNER-DENVER COMPANY, OF DENVER, COLORADO, A CORPORATION OF DELAWARE

CHUCK FOR ROCK DRILLS

Application filed May 3, 1928. Serial No. 274,767.

The present invention relates to chuck structures for rock drills and like tools, the object being to provide an effective steel holder having a long bearing and yet permitting easy introduction and removal of the lagged part of the steel.

In the accompanying drawings:

Figure 1 is a longitudinal sectional view through a such structure embodying the present invention.

Figures 2, 3, 4 and 5 are sectional views respectively on the correspondingly numbered lines of section of Figure 1.

Figure 6 is a longitudinal sectional view through a slightly modified form of structure.

Figure 7 is an end elevation of the sleeve.

Figure 8 is a side elevation of the front end portion thereof.

Figure 9 is a cross sectional view on the line 9—9 of Figure 6.

In the embodiment disclosed, a chuck housing 10 is employed fitted on to the front end of the usual cylinder bushing 11. In the housing and bushing is rotatably mounted a sleeve 12 having at its end a nut 13 that is in splined engagement with the hammer piston indicated at 14.

The sleeve is provided between its ends and in advance of the nut 13 with an internal rib 30 or flange 15 forming a front abutment shoulder 16. Into said front end of the sleeve is securely pressed a bushing 17 constituting a bearing for the rear end 18 of the steel 19. This steel is provided with the usual lugs 20.

A chuck member 21 is located in the housing in advance of the sleeve 12 and is interlocked therewith by interfitting teeth portions 22 at their adjacent ends. This chuck housing has a reduced front end 23 that extends through an inturned flange 24 formed on the front end of the housing, and constituting a retainer for the chuck member 21.

The chuck member 21 has an internal chamber 25 for the reception of the lugs 20 of the steel and the front wall of said chamber is provided with a bore 26 for the passage of the steel and oppositely disposed passageways 27 that permit the entrance of the lugs into the chamber 25. By reference to Figure 2, it will be noted that the walls of the bore 26 be-

tween the passageways 27 constitute bearings for the steel 19. In the rear portion of the chamber 25 are the usual abutment lugs 28 for the steel lugs 20 (see Figure 5), and the inner ends of these lugs constitute bearings 29 for the steel. Between the lugs 28 and the front wall 23 there are other bearing lugs 30 that engage opposite sides of the steel, as shown in Figures 3 and 4, these lugs being spaced apart to provide passageways 31 for the lugs of the steel. It will be noted by a comparison of Figures 2 and 3 that the bearings 26 of the front wall 23 and the bearings of the lugs 30 are at right angles and that the bearings 29 of the lugs 28 are in a different relation from either of the foregoing. As a consequence, it will be evident that a very long bearing is provided for the shank of the tool.

In Figures 6-9 inclusive, a slightly modified form of construction is shown. In this embodiment, the housing is designated 32 and contains a sleeve 33 having a nut 34 in its rear end for splined engagement with the hammer position. The sleeve in this instance is provided near its front end with a shoulder 35 against which is pressed into the sleeve from the rear, a bushing 36. Interposed between the nut 34 and bushing 36 is a spacing sleeve 37. The chuck member is designated 38 and is interfitted at its rear end with the front end of the sleeve 32 as shown at 39. The front wall of said chuck member 40 is provided with a bearing 41 for the shank of the tool 42 and is of the same formation as shown in Figure 2. The abutment lugs for the steel lugs 43 are in this structure formed in the front end of the sleeve at 44, while bearing lugs 45 corresponding to the lugs 30 of the first described structure are interposed between the front wall 40 and the bearing lugs 44. This structure obviously secures the same long bearing and yet permits the ready insertion of the tool into the chuck and its removal therefrom while maintaining it against accidental displacement.

From the foregoing, it was thought that the construction, operation and many advantages of the herein described invention will be apparent to those skilled in the art without

further description, and it will be understood that various changes in the size, shape, proportion and minor details of construction may be resorted to without departing from the spirit or sacrificing any of the advantages of the invention.

What I claim, is:

1. The combination with a housing, of a sleeve therein, a bearing bushing pressed into the sleeve, and a rotatable chuck member in advance of the sleeve having a plurality of relatively fixed bearings within the same spaced apart and at different points along its length for engagement with a lugged tool at different distances from the lugs thereof in advance thereof.
2. The combination with a housing, of a rotatable chuck therein having a chamber for receiving the lugged end of a steel and having abutments for the lugs thereof, said chamber having a front bearing for the steel, and bearings in the chamber between the front bearing and the lug abutments and spaced from both.
3. The combination with a housing, of a rotatable chuck therein having a chamber for receiving the lugged end of a steel and having abutments for the lugs thereof, said chamber having a front bearing for the steel, spaced bearing lugs in the chamber between the front bearing and the lug abutments, and spaced from both, said bearing lugs engaging the shank of the tool and spaced apart to permit the passage of the lugs.
4. The combination with a housing, of a rotatable sleeve therein having a nut in its rear end for splined engagement with a hammer piston, a bushing pressed into the front end of the sleeve and constituting a bearing for the rear end of a drill steel, a chambered chuck interlocked with the front end of the sleeve and having a relatively fixed front wall provided with a bore to form a bearing for the steel and having passageways for the entrance of the lugs of the steel into the chamber, abutments at the rear end of the chamber for the lugs, and spaced bearing lugs in the chamber between the front wall and abutments and adapted to bear against the steel, said bearing lugs being spaced from the abutments and from the front wall a distance sufficient to permit the passage therebetween of the lugs of such steel.
5. The combination with a housing, of a rotatable chuck therein having a chamber for receiving the lugged end of a steel and having abutments for the lugs thereof, said chuck having a front wall provided with a bore to form a bearing for the steel and having passageways to permit the entrance of the lugs to the chamber, said chuck having bearing lugs in the chamber that are behind and substantially in line with the passageways of the front wall, said bearing lugs being spaced from the front wall sufficiently to permit the

lugs to turn between them after passing the front wall to pass the bearing lugs to engage the abutments.

6. The combination with a housing, of a rotatable chuck therein having a chamber for receiving the lugged end of a steel and having abutments for the lugs thereof, said chuck having a front wall provided with a bore to form a bearing for the steel and having passageways to permit the entrance of the lugs to the chamber, said chuck having bearing lugs in the chamber that are behind and substantially in line with the passageways of the front wall, said bearing lugs being spaced from the front wall sufficiently to permit the lugs to turn between them after passing the front wall, and said bearing lugs being in advance of and offset with respect to the abutments and spaced therefrom to permit the lugs to turn behind the bearing lugs and engage the abutments.

In testimony whereof, I affix my signature.

AUGUST H. KATTERJOHN.
